TRANSMITTING APPARATUS FOR COMMUNICATION SYSTEMS USING FREQUENCY MODULATION

Adrian R. Doucette, Swissvale, and Paul E. Lorentzen, Pittsburgh, Pa., assignors to The Union Switch and Signal Company, Swissvale, Pa., a corporation of Pennsylvania

Application April 5, 1947, Serial No. 739,628

5 Claims. (Cl. 332—19)

1

Our invention relates to transmitting apparatus for a communication system using frequency modulation, and more particularly to transmitting apparatus for an inductive carrier communication system using frequency modulation.

A reactance tube modulator is frequently used in the transmitter, that is, in the transmitting apparatus of a communication system using frequency modulation. Such an arrangement generally includes inductance or choke coils in the input of the modulator and between the modulator and the oscillator. These devices may reduce the sensitivity of modulation. That is, the amount of deviation (modulation) of the center carrier frequency for a given unit of the signal or modulating current may be reduced. Furthermore, such choke coils are of relatively large and expensive construction. In portable units for communication systems of the type here involved, it is important to reduce the number of parts required and to simplify and minimize their construction and size in order that the unit can easily be handled. Also, high modulation sensitivity and a high order of frequency stability are requisites for such units.

Accordingly, a main object of our invention is the provision of improved transmitting apparatus for communication systems using frequency modulation.

A more specific object of our invention is the provision of an F. M. transmitter incorporating novel means to give high modulation sensitivity and a high order of frequency stability.

Again, a feature of our invention is the provision of an F. M. transmitter incorporating a novel automatic frequency control and method of applying voice frequencies to the modulator.

Specifically, a feature of our invention is the provision of transmitting apparatus for a portable unit of an inductive carrier railway train communication system using frequency modulation.

Other features, objects and advantages of our invention will appear as the specification progresses.

The foregoing objects, features and advantages of our invention are attained by the provision of an oscillator-modulator in which high frequency inductance or choke coils are eliminated. This gives a high sensitivity of modulation and reduces the size and cost of construction.

For frequency stability an automatic frequency control is provided by taking a voltage from the oscillator and applying it to a buffer tube to the input of which there is connected a resistance

2

load from which the carrier is filtered. Voltage applied to the buffer tube is amplified and limited and applied to a discriminator network. The voltage output from the discriminator network and a voltage taken from the resistance load are combined and applied to the grid of the modulator to affect automatic frequency control of the oscillator. Audio voltages created in a microphone are applied to a pre-emphasis circuit which is coupled to the grid of a modulator tube in multiple with the output of the discriminator to form an adio frequency load for the modulation of the carrier frequency. This pre-emphasis circuit also serves as a filter to shunt the audio frequency voltages appearing at the output of a discriminator.

For a better understanding of our invention reference may be had to the accompanying drawing, which is a diagrammatic view showing a preferred construction of our invention when used with a portable unit of an inductive carrier communication system.

It is to be understood that our invention is not limited to a portable unit and this one application serves to illustrate the utility of the invention.

Referring to the drawing, the reference character PU indicates a power unit made up of a low voltage battery 10 and a tuned alternator 20 TA, the alternator being used to convert the low direct voltage from the battery into a unidirectional voltage for energizing the anode circuits of the electron tubes.

The battery 10 may be of any suitable voltage such as a six-volt battery and the tuned alternator TA may be of any one of several well-known types.

It is sufficient for this application to point out that an operating magnet 11 of the tuned alternator is energized from battery 10 to attract a tuned contact member 14 to engage a contact 12 and shunt the magnet 11. This sets the tuned contact member 14 into vibration, the rate of vibration being determined by the proportioning of the member 14. Vibration of member 14 to alternately engage contacts 12 and 15, causes current from battery 10 to alternately flow in the two half portions of primary winding 13 of a transformer T1 and induce an alternating voltage in secondary winding 16 of the transformer. The frequency of this alternating voltage is determined by the rate of vibration of the member 14. The outside terminals of secondary winding 16 are connected to contacts 17 and 18 which are alternately engaged by the member 14 and the

alternating voltage is rectified to create a unidirectional voltage between mid terminal of winding 16 and ground electrode 19 connected to the pivot point of the vibrating member 14, the mid terminal of winding 16 being the positive terminal.

An oscillator OSC comprising an electron tube V2 and associated circuits, is provided. The tube V2 is disclosed as a pentode but other types of tubes can be used. Filament 20 of the tube V2 forms the cathode, a mid point of the filament being connected to an auxiliary grid 23 in the usual manner. The filament 20 is heated from battery 10, the filament 20 being included in a filament circuit along with the filaments of two other tubes V1 and V3, to be referred to later, and which filament circuit can be traced from the positive terminal of battery 10 through ground electrodes 19 and 24, filament 20 of tube V2, wire 31, filament 32 of tube V3 and resistor 33 in multiple, wire 34, the two half portions of filament 28 of tube V1 in multiple, and wire 35 to the negative terminal of battery 10. An anode-cathode circuit for tube V2 is powered from the power unit, the circuit extending from the mid terminal of winding 16 of the transformer T1 through a choke coil 40, a tuned primary winding 21 of an output transformer T2, anode 22 and tube space to cathode 20, ground electrodes 24 and 19, contact member 14 of the tuned alternator, and alternately through the contacts 17 and 18 to the outside terminals of winding 16.

An oscillatory circuit comprising an inductor L1 and a capacitor C1 is connected across grids 25 and 26 of tube V2, a capacitor C16 being interposed in the connection to grid 26 and a resistor R1 being disposed between grid 26 and ground. The parts are proportioned so that oscillations of a predetermined carrier frequency having a center frequency of say, frequency f_1 , are created. The frequency of the oscillations is primarily determined by the inductance L1 and capacitance C2, but it is also controlled by the reactance of a modulator tube V1 connected to the oscillatory circuit in the usual way.

The modulator tube V1 is shown as a pentode similar to the oscillator tube V2. The anode circuit of tube V1 is powered from the power unit, its anode 27 being connected to the mid terminal of secondary winding 16 of transformer T1 through a portion of the inductor L1 of the oscillatory circuit, and its cathode 28 being connected to ground through the filament circuit of the tubes. Voltage from the power unit is applied to grid 29 of tube V1 through a resistance R12 having a by-pass capacitor C11. Also, a capacitor C2 is connected between the anode 27 and the control grid 30 of the tube V1. It is clear that voltage variations applied to control grid 30 of tube V1 to cause corresponding variations in the reactance of the tube will in turn serve to frequency modulate the oscillations created by the oscillator. Furthermore, it is clear that the modulation of the carrier frequency will be repeated in the current supplied to a load circuit connected to secondary winding 41 of the output transformer T2.

For automatic frequency control, a voltage is taken from the oscillator through a capacitor C10 and applied to a control grid 36 of tube V3, resistors R9 and R10 in series being connected between grid 36 and ground to form a load circuit for the input of the tube V3. The tube V3 is disclosed as a pentode and this tube serves as a buffer tube. Anode 37 of tube V3 is powered from

the power unit through resistor R7 and winding L4 of a discriminator network, to be described shortly. Also, a voltage is applied to grid 38 of tube V3 from the power unit through resistors R1 and R6 in series, a capacitor C13 being connected between the junction terminal of resistors R7 and R6 and ground and a capacitor C15 being connected between grid 38 and ground. Thus the voltage applied to control grid 36 of tube V3 is amplified and limited in the anode circuit of this tube and is supplied to the resonant circuit including winding L4 and capacitor C4 of the discriminator network. This resonant circuit is in turn coupled to a second resonant circuit comprising winding L3 and a capacitor C3, and a coupling capacitor C6 is connected between a center tap of winding L3 and the top terminal of winding L4. The outside terminals of the resonant circuit L3—C3 are connected to rectifiers D1 and D2, respectively, and the center terminal of winding L3 is connected to the junction terminal of resistors R4 and R5, the outside terminals of which resistors are connected to the output sides of the rectifiers D1 and D2. The rectifiers D1 and D2 may be of any suitable type and are shown conventionally. Preferably these rectifiers are of the copper oxide type but other types can be used. Consequently there is created across resistors R4 and R5 of the output of the discriminator network a direct voltage that corresponds to the frequency deviation from the center frequency of the voltage applied to tube V3 from the oscillator. This direct voltage will have a polarity according as the deviation of the frequency is above or below the center frequency of the oscillator.

The voltage applied to grid 36 of tube V3 will cause grid current to flow during the half cycle the grid is positive with respect to the cathode 32. This rectifying action of the grid circuit of tube V3 creates a voltage drop across resistors R9 and R10 connected to the input of the tube. The carrier frequency is by-passed from resistor R10 by capacitor C9 and a direct voltage appears across this resistor, the top terminal of resistor R10, that is the junction terminal of the two resistors, being negative with respect to ground.

The top or outside terminal of resistor R4 in the output of the discriminator is connected to grid 30 of the modulator tube V1 by wire 42 and resistor R1, a capacitor C12 being connected between wire 42 and ground. The junction terminal of resistors R9 and R10 is connected to the outside terminal of resistor R5 of the discriminator network, and thus it is coupled to the grid of the modulator tube V1 through the resistors R5, R4 and R1. It is to be seen therefore that the modulator tube V1 is provided with a grid bias voltage which is the resultant of the voltage derived from resistor R10 and the voltage created through the discriminator network.

As long as the oscillator delivers the center frequency, the voltage created across the discriminator is zero and the bias voltage applied to the modulator tube V1 is only that derived from resistor R10 and this voltage remains substantially constant due to the substantially constant amplitude of the oscillations. If the oscillations deviate to rise above the center frequency, the output voltage of the discriminator combines with the voltage derived from the resistor R10 to vary the bias of the modulator tube V1 and vary its reactance as required to bring the oscillations back to the center frequency. Similarly, if the oscillations fall below the center frequency,

the output of the voltage of the discriminator is of the opposite polarity and combines with the voltage derived from resistor R10 to vary the reactance of tube V1 to bring the oscillations back to the center frequency.

Also, the amplitude of the oscillations and the resulting voltage developed across resistor R10 are dependent both upon the voltage of battery 10 and the voltage developed by the tuned alternator driven from battery 10. Such variation of the voltage developed at resistor R10 results in a corresponding change in the voltage applied to the modulator tube V1 tending to correct for changes in the center frequency of the oscillations due to the changes in the voltage of battery 10. That is, the automatic frequency control voltage is dependent upon the voltage of the power supply and in this way a large degree of frequency control for frequency changes due to voltage changes of the power supply are obtained.

A microphone M is provided with a circuit that includes resistor R3 and low voltage battery 10. Thus a voltage varied at the audio frequency developed by speaking into the microphone is created across the resistor R3. Resistor R3 is coupled to a resistor R2 through a capacitor C8, resistor R2 and capacitor C8 forming a pre-emphasis circuit. This pre-emphasis circuit is coupled to the combination of resistors R4 and R5 of the discriminator through a capacitor C7 and the audio frequencies of the microphone circuit current are applied to the control grid 30 of the modulator tube V1 with the result that the center or carrier frequency of the oscillator is frequency modulated by the voice frequencies.

At the same time the elements C7-R2 and C8-R3 form a filter network by which the audio voltages developed across the resistors R5 and R4 of the discriminator due to the frequency modulation of the carrier by the voice frequency are suppressed.

That is, the voltage developed across resistors R4 and R5 due to the slow shift of the center frequency of the oscillations because of circuit conditions is not filtered and the voltage is applied to the modulator tube but the relatively high frequency audio voltages developed across resistors R4 and R5 are by-passed by the filter network.

Apparatus such as here disclosed has the advantages that a high modulation sensitivity is effected, frequency stability of high order is obtained and pre-emphasis of the audio frequency is provided with the pre-emphasis circuit serving as a filter to suppress the audio voltages resulting from the audio frequency modulation of the carrier. Also, the apparatus is relatively simple and light to be particularly adaptable for a portable unit.

Although we have herein shown and described but one form of transmitting apparatus for a communication system using frequency modulation embodying our invention, it is to be understood that various changes and modifications may be made therein within the scope of the appended claims without departing from the spirit and scope of our invention.

Having thus described our invention, what we claim is:

1. In transmitting apparatus for a communication system using frequency modulation, the combination comprising, an electron tube oscillator to supply a carrier current of a given center frequency, a modulator electron tube connected to said oscillator to frequency modulate said car-

rier current according to the frequency of a communication current applied to a control grid of the modulator tube, a buffer electron tube, means including a capacitor to couple said oscillator to a control grid of said buffer tube to apply thereto a voltage having a frequency of said carrier current, a discriminator network connected to the output of said buffer tube to provide a direct voltage proportional to deviations of the frequency of said voltage from said center frequency, a resistance load circuit including two resistors in series connected to said control grid of said buffer tube to create a direct voltage proportional to the amplitude of said carrier current, circuit means to connect the output of said discriminator and said load circuit to said control grid of said modulator tube to stabilize said center frequency of said oscillator due to the bias voltage thus applied to the modulator tube, and a filter network connected to said discriminator to by-pass the voltage created by the discriminator due to said communication current.

2. In transmitting apparatus for a communication system using frequency modulation, the combination comprising, an electron tube oscillator to supply a carrier current of a given center frequency, a modulator electron tube connected to said oscillator to frequency modulate said carrier current according to the frequency of a communication current applied to a control grid of the modulator tube, a buffer electron tube, means including a capacitor to couple said oscillator to a control grid of said buffer tube to apply thereto a voltage having a frequency of said carrier current, a discriminator network connected to the output of said buffer tube to provide a direct voltage proportional to deviations of the frequency of said voltage from said center frequency, a load circuit including a first and a second resistor in series connected between said control grid of said buffer tube and ground, a capacitor connected across said second resistor to by-pass the carrier and create a direct voltage across said second resistor due to the carrier frequency voltage applied to said buffer tube, a control circuit including said second resistor and the output of said discriminator connected to said control grid of said modulator tube to stabilize the center frequency of said oscillator by the resultant of the voltage derived from said discriminator and the voltage derived from said load circuit, and filter means connected to said control circuit to by-pass from said modulator tube voltages created by said discriminator due to the modulation of said carrier current by said communication current.

3. In transmitting apparatus for a communication system using frequency modulation, the combination comprising, an electron tube oscillator to supply a carrier current of a given center frequency, a modulator electron tube connected to said oscillator to frequency modulate said carrier current according to the frequency of a communication current applied to a control grid of the modulator tube, a buffer electron tube, means including a capacitor to couple said oscillator to a control grid of said buffer tube to apply thereto a voltage having a frequency of said carrier current, a discriminator network connected to the output of said buffer tube to provide a direct voltage proportional to deviations of the frequency of said voltage from said center frequency, a load circuit including resistance connected between said control grid of said buffer tube and ground and having a by-pass capacitor

connected across at least a portion of said resistance to create a direct voltage due to the grid current caused to flow in said buffer tube by the voltage derived from said oscillator, said portion of said resistance and the output of said discriminator connected in series to said control grid of said modulator tube to stabilize the center frequency of said oscillator due to the voltages derived from said discriminator and said load circuit, and filter means connected to the output of said discriminator to divert from the modulator tube the voltages created by the discriminator due to the modulation of said carrier by said communication current.

4. In transmitting apparatus for a communication system using frequency modulation, the combination comprising, an electron tube oscillator to supply a carrier current of a given center frequency, a modulator electron tube connected to said oscillator to frequency modulate said carrier current according to voltage variations applied to a control grid of said modulator tube, a buffer electron tube, a connection including a capacitor to couple said oscillator to a control grid of said buffer tube to apply thereto a voltage having the frequency of said carrier current, a discriminator network having an output including a first and a second resistor in series, said network connected to said buffer tube to create across said first and second resistors a direct voltage corresponding to deviations of the voltage applied to said buffer tube from said center frequency, a load circuit including resistance and a by-pass capacitor connected between said control grid and a cathode of said buffer tube to create a direct voltage proportional to the amplitude of the voltage applied to said control grid of said buffer tube, means to connect at least a portion of the resistance of said load circuit and said first and second resistors to said control grid of said modulator tube to stabilize the center frequency of said oscillator, a microphone circuit including a microphone and a current source, a pre-emphasis circuit including a resistor and a capacitor coupled to said microphone circuit, means

including a capacitor to couple said pre-emphasis circuit to said control grid of said modulator tube to frequency modulate said carrier current by voice frequencies of said microphone, and said 5 pre-emphasis circuit and said last mentioned capacitor forming a filter circuit network which removes the audio voltages created across said first and second resistors.

5. In transmitting apparatus for a communication system using frequency modulation, the combination comprising, a power source of a given direct voltage, an electron tube oscillator receiving energy from said power source to generate a carrier current of a given center frequency, a modulator electron tube connected to said oscillator to frequency modulate said carrier current according to voltages applied to a control grid of said modulator tube, another electron tube having a control grid capacity coupled to said oscillator to receive a voltage having the frequency of said carrier current, a discriminator network connected to said another tube to create a direct voltage corresponding to deviations of the voltage received from said oscillator from said center frequency, a resistance load circuit connected across said control grid and cathode of said another tube to create a direct voltage proportional to the amplitude of the voltage received from said oscillator, and circuit 20 means to couple said load circuit and said discriminator to said control grid of said modulator tube to minimize deviations of the frequency of the carrier current from said center frequency due to changes in the voltage of said power source from said given direct voltage.
